HAND REMOVER FOR CLOCKS AND
INSTRUMENTS

John Maken and John A. Lennox, Pittsburgh, Pa.

Application May 3, 1948, Serial No. 24,867

1 Claim. (Cl. 29—231)

1

This invention relates to improvements in implements for use in repairing clocks and like mechanisms, and more particularly to a device for conveniently removing the hands of the clocks or like mechanisms.

An object of the invention is to provide a device which is simple in construction and operation, and which is adapted to remove the hands of clocks or like mechanisms without damage to the arbor on which the hands are mounted or without damage to the mechanisms carrying these hands.

Other objects and advantages will become apparent as the invention is further described, claimed and illustrated in the accompanying drawing in which:

Figure 1 is a side elevational view of an embodiment of the invention in a position to remove the hands of a clock or like mechanism;

Figure 2 is a vertical sectional view on the line 2—2 of Figure 1;

Figure 3 is a cross sectional view on the line 3—3 of Figure 1;

Figure 4 is a detailed fragmentary cross sectional view on the line 4—4 of Figure 1;

Figure 5 is a detailed fragmentary view, partly in section, of the screw and the removable tip therefor, and

Figure 6 is a plan view of the blank from which the device is formed.

Referring more in detail to the drawing, the implement embodying the invention is designated by the reference numeral 10. The implement comprises a yoke 11, which is formed from the blank shown in Figure 6. The yoke 11 comprises a base portion 12, provided with a V-shaped slot 13, so formed that the apex of the V is inwardly of the forward end of the base portion. The ends of the base portion formed by the slot are inwardly and downwardly bevelled as shown at 14. The bevel permits the base to be inserted under the hands 15 and 16 that are connected to the arbor 17 of the mechanism 18.

At the rear of the base portion, the yoke is bent upwardly along the dotted line 19 to form the vertical portion 20. The portion 20 being bent on the dotted lines 21 and 22 respectively forms the parallel arms 23 and 24 respectively. These arms overlie the base portion 12, and are spaced from the base portion in parallel relation thereto by the wings 25 and 26 formed on the arms at the rear ends thereof.

Each of the arms is provided with a longitudinally extending elongated slot 27, which are in alignment with each other on a horizontal plane.

Slidably mounted in the slots 27 are the reduced portions 28 of the screw supporting block 29.

2

The block 29 has a centrally located tapped bore 30 to receive the press screw 31. The screw 31 is provided with a knurled knob 32 on the upper end thereof, whereby the screw is manipulated.

The lower end of the screw is received in the tapped socket 33 of the removable bearing tip 34.

The block 29 being slidably mounted in the slots 27 by reason of the reduced portions 28, the block can be moved with relation to the arbor 17 until the tip 34 will bear evenly on the arbor 17.

In use, the base is inserted under the hands 15 and 16, as shown in Figure 1. The screw 31 is moved downwardly until the tip 34 is bearing evenly on the arbor 17. The block 29 being movable, a true alinement is achieved between the arbor 17 and the tip. By further turning of the knob 32, the base portion 12 is moved upwardly, pulling the hands from the arbor.

It is believed that from the foregoing description, the construction and manner of operation of the implement will be apparent to those skilled in the art, and it is to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

30. A tool, comprising a yoke, having a base portion, a vertical portion, arms on said vertical portion in parallel alinement with each other and in elevated parallel alinement with said base, a V-shaped slot in said base portion and the edge of 35 the base outwardly of the slot being inwardly and downwardly bevelled, parallel alined slots in said arms, a block movably mounted in said slots, a screw having a removable bearing tip on its lower end and a knurled knob on its upper end threadably mounted in said block for movement away from and toward said base portion.

JOHN MAKEN.

JOHN A. LENNOX.
